Attest.

United States Patent Office.

THOMAS E. MOORE, OF COLUMBUS, OHIO.

Letters Patent No. 105,114, dated July 5, 1870.

IMPROVEMENT IN PAPER-FILES.

The Schedule referred to in these Letters Patent and making part of the same.

To all whom it may concern:

Be it known that I, THOMAS E. MOORE, of Columbus, in the county of Franklin and in the State of Ohio, have invented certain new and useful Improvements in Paper-Files; and do hereby declare that the following is a full, clear, and exact description thereof, reference being had to the accompanying drawing and to the letters of reference marked thereon making a part of this specification.

The nature of my invention consists in the construction of a wire spring for paper-files, in such a manner that it will operate on both sides of the board, and, also, in applying to such files a covering-flap, as will be described.

In order to enable others skilled in the art to which my invention appertains to make and use the same, I will now proceed to describe its construction and operation, referring to the annexed drawing in which—

Figure 1 is a plan view of my paper-file, the cover being thrown to one side, and

Figure 2 is an enlarged sectional side view of the same.

Figure 3 represents an edge view.

A represents a flat board, of any size desired, said board having a rectangular hole cut out near the edges of its sides, at or about the center.

B is the spring, made of suitable wire, in the following manner: A portion of the wire is bent so as to form a spiral spring, a, to be inserted in the notch on one side of the board A.

The outer end b of the wire is carried straight to the edge of the board, and then along the edge of the same, and crosses the board at a suitable distance from its end, and then back along the other or opposite edge of the board to a point opposite the hole on this side, where it forms a hook, d.

The inner end e of the coil spring a is carried through the spring, emerging on the under side of the board, when it is carried parallel to the end b, forming the same turns or bends, until it reaches the point opposite the rectangular hole where the wire b formed its hook d. At this point the wire e also forms a hook, g.

At the point where the wires b and e turn from the coil spring a to follow the edge of the board, they form loops or bends, e and f, as shown in fig. 1. The two wires b and e, or, rather, ends of the same wire, thus form clamps or holders, one on each side of the board, at the same end from the center.

In like manner another spring, B, is placed on the

board, extending toward the other end, the two springs being connected in the following manner: The hooks d and g, of each spring, are hooked into the loops e and f of the other spring.

To distinguish the two springs, I have marked the different parts of the second spring mentioned with the same letters as the first, but placed a number one (1) after each.

When the springs are thus connected, the spiral portions a a are liable to fall down further on one side of the board than on the other, which is obviated by inserting the straight wire h in the two coils, as shown in fig. 1.

At one end of the board A is tacked, or otherwise secured, a cover, C, of oil-cloth, or other suitable material, of any desired length, and of the same width as the board. The ends of this cover extend down along the sides of the board, and are placed under the springs B B, to cover any paper held by the same. The ends can then be lapped over on the opposite side, and held by the spring on that side.

The advantages of my paper-file over others now in use are, mainly, that both sides of the board can be used. For instance, one side can be used for unsettled and the other for settled bills, or one side for short and the other for long papers; also, securing the clamps to the board by the wire, forming clamp and spring without use of rivets.

By the use of clamps on both sides of the board, pressure is equal, and the board will not be apt to warp. The cover preserves the papers from injury while being carried about in the pocket. The paper-file can even answer all the purposes of a pocket-book.

Having thus fully described my invention,

What I claim as new, and desire to secure by Letters Patent, is—

1. The clamps B B, formed of the wires b b e e', coils a a', hooks d g, and loops c f, and used for operation on both sides of the board A, substantially as set forth.

2. In combination with the wire clamps B B, as described and arranged upon the board A, the cover C, substantially as set forth.

In testimony that I claim the foregoing, I have hereunto set my hand this 4th day of January, 1870.

THOMAS E. MOORE.
